JOURNAL BOX AND LID THEREFOR

Nels E. Flodin and Theodore R. Weber, Latrobe,
Pa., assignors to American Locomotive Com-
pany, New York, N. Y., a corporation of New
York

Application September 1, 1936, Serial No. 98,878

3 Claims. (Cl. 308—47)

This invention relates to journal boxes and lids therefor for railway vehicles, and particularly to a spring-actuated lid.

The principal object of this invention is to provide a spring-actuated journal box lid comprising various novel features in a well-known type of lid.

The invention is illustrated in the accompanying drawings in which Fig. 1 is a front view of a conventional type of box and the lid of the present invention, a part thereof being broken away; Fig. 2 is a section on the line II—II of Fig. 1, but showing the spring in full in side elevation, and a portion of the box, the spring energizing and retaining member or hood being closed and the spring energized as in Fig. 1; Fig. 3 is a section taken on the line III—III of Fig. 1, showing a portion of the box, the member or hood being open and the spring deenergized; Fig. 4 is a fragmental section on the line IV—IV of Fig. 2; Fig. 5 is a fragmental section on the line V—V of Fig. 2; Fig. 6 is a fragmental side view of the cover; Fig. 7 is a view similar to Fig. 6 but showing the pintle eye rolled in the opposite direction from that of Fig. 6; Fig. 8 shows fragmentally the stamped sheet from which the portion shown in Fig. 6 is formed; Fig. 9 shows fragmentally the stamped sheet from which the portion shown in Fig. 7 is formed; and Fig. 10 is an enlarged view similar to Fig. 2, with certain parts not shown.

Referring in detail to the drawings, wherein a preferred embodiment of the invention is shown, the journal box 1 is shown fragmentally, that being deemed all that is necessary for a full understanding of the present invention. It is the conventional A. A. R. type and is provided at its front face with the usual opening 2. A member, preferably in the form of a lug 3, is carried by the box beyond the upper side of the opening 2 and centrally thereof. The lug is provided at its front with a cam face 4 which is directed to make a definite angle with the face 5 of the box. The lug is further provided at its top with a cam face 6 and with an orifice 7 in which a hinge pintle 8 is mounted with its opposite end portions 9 and 10 extending from the opposite sides of the lug.

The lid of the present invention, indicated generally by the reference numeral 11, resembles in many respects the lid shown in patent to John L. Mohun, No. 1,922,597, but the present lid is an improvement over the Mohun lid in various particulars, as will later more fully appear.

The lid comprises a cover 12 which, when closed, seats upon the margins 13 of the box to

completely close the opening 2. It is shaped from a stamping, and in the main is quite similar to the cover of the said Mohun patent, and similarly comprises a body portion 14, side and bottom flanges 15 for overlapping the side and bottom margins 13 respectively of the box, a pair of eyes 16 mounted on the pintle 8, one at each side of the lug 3, and a top flange 17 extending from the top edge of the body portion 14 upwardly and inwardly to the eyes 16 to which it is integrally connected at the seams thereof.

In the Mohun construction the connections of the outer ends of the eyes with the adjacent portions of the top flange occasionally develop weak spots. Occasionally these connections start to crack at these points under severe service conditions, and the connections thus weakened continue to crack until at times an eye is entirely severed from the body portion.

In the cover of the present invention the above defect is overcome by doing away with the tongues of the Mohun cover and continuing each side flange 15 upwardly to its adjacent eye, forming thereby an upwardly directed extension 18 on each of the side flanges 15 above the body portion 14 integrally connected at its outer edge with the adjacent end of the top flange 17 and with a part of the outer end of the adjacent eye 16. This provides an integral union of said body portion, eye, side flange and top flange whereby the joint between said body portion and eye is materially reinforced.

Fig. 6 shows the eye 16 rolled clockwise, as viewed therein, providing a seam 19 concealed from the front, which in usual practice is sealed by welding, thereby strengthening the jointures between the connecting flange 17 and eyes. In Fig. 7 the eye is rolled in the opposite direction, providing an exposed seam and a slightly different style of union between the eyes and cover.

Instead of the straight tongues of the Mohun construction which are for holding the pintle against displacement, curved tabs or tongues 20, of a well-known construction, are employed. There is a tongue 20 at the outer end of each eye, and the tongue is formed by cutting or stamping out a portion of the end of its respective eye in a manner to leave its rear edge integrally connected with the eye, and the remainder of the tongue free from the eye in order that it may be rolled or bent into the path of the pintle 8 for holding the pintle in place, and re-bent out of the path of the pintle when it is desired to remove the pintle, in which case only one tongue need be re-bent.

5 In forming the tongue from the eye (which is preferably accomplished while the flat sheet metal is being stamped, and cut as found necessary, before the cover and associated integral parts are shaped) the lower edge of the tongue is stamped or cut at an appreciable distance in both the types shown in Figs. 6 and 7 from what will later be the seam 19 to thus dispose the lower edge of the tongue opposite the outer end of the 10 seam, and well spaced therefrom, thereby preserving ample metal in the eye adjacent the end of the seam in order that the seam will extend to the extreme outer end of the eye to facilitate the formation of the integral union of the extensions 18 with the eyes, as aforementioned, and in order to give maximum strength to the jointure between the eye and top flange 17. The manner of cutting or stamping the tongue from the eyes of Figs. 6 and 7 is best shown in Figs. 8 15 and 9 respectively, which show fragmental portions of the flat sheet. The portion of the metal which is left intact, and which in the formed eye will be adjacent the seam, is indicated in each instance by the numerals 21 and 22 respectively. The eyes are slightly elongated, as shown, frontwardly and rearwardly in the usual manner, to facilitate seating of the cover upon the box but their minor axes are substantially equal to the diameter of the pintle to make a working 20 fit therewith.

25 A member 23 providing a hood, in this latter respect similar to the hood of the Mohun patent, and whose function, as will later be more fully described, is principally for energizing and deenergizing the spring means of the lid, for retaining the spring means in energized position and for pressing the cover upon the box, is disposed at the front of the cover. It comprises side walls 24, each having at its upper portion an eye 25 30 mounted upon the pintle 8 between the side of the lug 3 and the inner end of the eye 16 adjacent thereto, thereby providing an articulation whereby the member and cover may be swung as a unit about the axis of the pintle to cover-open 35 and cover-closed positions in the usual manner, and whereby the member may have swinging movement from open, spring means deenergized position toward the cover to closed, spring means energized position, at which position the member holds the spring means in energized position and presses the cover upon the box, as will later be described, and whereby the member may be swung open to spring means deenergized position, the spring means being energized during closing 40 movement and deenergized during opening movement in a manner, generally speaking, somewhat similar to the operation of the Mohun lid.

45 Spring means 26, in the main similar to the spring means of the Mohun patent, functioning to effect a holding of the cover 12 in both closed and open positions, is disposed between the member 23 and the cover. It comprises two coils 27 and 28, disposed each in a depression 29 formed in the cover and secured therein, somewhat above the center of the cover, by securing means 30, which, in the present instance, is formed of a plate bent, at its free end portions, to conform to the curvature of the coils, and secured to the cover by rivets 31.

50 Each of the coils, at one end thereof, has an upwardly extending integral branch 32 connected at their upper ends by a central portion 33 upon which is mounted an anti-friction roller 34 which engages the cam face 4 when the cover is closed 55 and the cam face 8 when the cover is open, in

the usual manner. Each of the coils, at the other end thereof, has an upwardly extending integral branch 35, the upper end of which is free, this free end of the branch having an end portion 36 bent in a direction upwardly away from the coil and outwardly from the branch 32 adjacent thereto. The end of the end portion is bent inwardly, providing a rounded surface 37 which engages the inner face of the front wall 38 of the member 23. This wall, opposite each of the 10 end portions 36, is provided with an angular portion 39 which comprises a relatively long side 40, preferably somewhat curved, as shown. This side extends from its end, which initially engages the rounded surface 37 when the spring 15 means is in open deenergized position and the member is likewise in open spring means deenergized position, substantially as shown in Fig. 3, in a direction, when the member is in closed position, upwardly away from the respective coil and inwardly toward the plane of the cover 12 whereby, during the swinging movement of the member toward the cover (toward closed position), swinging movement is imparted to the branch 35 about its respective coil toward its 20 adjacent branch 32 by the rounded surface 37 engaging the side 40 adjacent thereto. During this operation, and due to the direction of the side 40, the energization of the spring means is enhanced and the spring means becomes overenergized when the rounded surface 37 arrives at the vertex 41 of the angular portion 39. At this point of energization the crest 42 of the rounded surface 37 is in engagement with the vertex 41 and the member 23 is near its closed spring means 25 energized position.

30 The circular arc 43 struck about the center or axis of the pintle 8 and tangent to the vertex 41 (the vertex being somewhat rounded), as viewed in Fig. 10, indicates approximately the 35 line at a point of which the crest 42 will be located when it engages the vertex 41, and from which can be seen the amount of overenergization there will be, which is measured approximately by the distance between the arc and the crest 42, as 40 shown in its final position.

35 The angular portion 39 further comprises the relatively short side 44 which extends from the vertex in a general direction away from the respective coil and abruptly away from the plane 45 of the cover, thereby providing an abutment, or a lock so to speak, for the spring means branch 35. During the final swinging movement of the member 23 to closed position the crest 42 leaves the vertex 41, and in fact severs engagement entirely with the member 23, and another part of the end portion 36 comes into engagement with the side or abutment 44 near the vertex. During this final closing swinging movement of the member a comparatively small portion of the side 44, that portion between the arc 43 and concentric arc 45, is traversed by the bent end portion 36 of the spring means, the arc 45 being struck from the center or axis of the pintle as a center through the final point *a* of engagement 50 between the member and the branch 35, while a comparatively large portion of the bent end portion 36 of the spring means traverses the member during this final closing period. During this period the spring means recoils, becoming 55 partially deenergized until it becomes normally energized upon reaching the engaging point *a*. While considerable force is required to compress the spring means to the point of engagement of the crest with the vertex, further movement of 60

the member toward closed position is practically automatic, the recoiling action of the spring means operating to bring the member to final closed position quickly with considerable force.

5 The spring means is thus held by the abutment of the member 23 in so-called locked energized position, and the member is held closed by the force of the spring means branch against the abutment and forced about its pintle axis down-
 10 wardly against the cover to hold the cover, when closed, in spring-pressed engagement against the box, the pressure of the member upon the cover being at its lower edge, the side walls 24 being cut away at their edges adjacent the cover to a
 15 slight extent, providing clearance spaces between these edges and the cover, as shown in Fig. 2. This overenergizing and partial deenergizing of the spring means to provide for the desired functioning, as aforesaid, of the abutment
 20 is novel in connection with journal box lids as far as is known, but the effectiveness of the abutment thus provided depends in large measure upon the angle that the side 46 at the locality of the point *a* makes with the cam face 4 which
 25 is indicated approximately by the angle α (Fig. 10) between the line *b* which passes through the point *a* tangent to the surface thereof and the line *c* drawn through the cam face 4.

While in the preferred embodiment the branches 35 are shown with the bent portions 36, it will be noted that instead thereof the branches 35 may be turned toward each other similar to the branches 32 and a roller similar to the roller 34 mounted on these end portions 35 for engagement with the member, this roller finally engaging the member at the points *a*; or each branch 35 may be formed at its end into a sharp hook that will engage the member, the hook finally seating at the point *a*. These two possible modifications present objections however as they do not provide for tolerance due to inaccuracies in manufacture as does the bent portions 36 of the branches 35 which are made of sufficient length to take care of all tolerance. Furthermore a sharp hook, as above suggested, does not lend itself for a satisfactory operation of the member.

To cheapen the cost of manufacture, the cover is stamped and pressed into shape and the eyes thereof formed by rolling portions of the stamping. Likewise the member 23 is stamped and pressed into shape and its eyes are formed by stamping crifices therein. These methods of manufacture do not insure mathematical accuracy in duplication of the parts. This also is true of the spring means due to the method of forming it desirable for reduction in cost of manufacture. The result is that the points of engagement between the various parts may not be precisely the same in each lid. Principally the location of the point *a* on the member 23 may vary as well as the location of the vertex of the angular portion 39. Likewise there may be a variation in the location of the crest 42 and also 65 the point of the branch 35 which contacts with the point *a* of the member. It is especially desirable that the construction be designed to provide for a tolerance between the point of contact of the branch 35 with the member so that 70 they will properly function. This is amply taken care of in the present design by providing the substantially straight bent portion of the branch 35 that is made of sufficient length to take care of all such possible inaccuracies in manufacture. 75 Likewise the present method followed in the

manufacture of the member 23 results in forming the vertex, or more accurately the vertex and the surface in the immediate locality thereof, blunt or rounded, as has been described, which admirably lends itself to the suitable functioning of the member and spring means, as has been described, wherein the branch 35 is finally seated slightly above the vertex and the angular portion above the point *a* serves as an abutment or so-called locking means for the 10 branch 35.

The present invention however, is not limited to this specific construction which, as aforescribed, is chiefly brought about on account of pursuing a method of manufacture that will 15 cheapen the cost thereof.

The same desirable ends sought will be accomplished if the vertex of the angle is made sharp instead of rounded, in which case the bent end portion of the branch 35 will ride upon this sharp 20 vertex edge and finally come to rest in seated position thereon, or the surface just above the sharp vertex edge may be flat and of the same angularity as the straight bent portion of the branch 35 when the parts are in normal operable position, in which case the straight bent portion will rest upon the flat surface. In this case the retention of the spring means in its final energized position and the action thereof to exert a force upon the member 23 tending to turn 30 it downwardly about its pintle axis and to effect a pressing thereby upon the cover resulting in holding the cover in spring-pressed engagement, when closed, upon the box would be due to the engagement of the sharp vertex edge 35 (or flat surface) by the bent portion of the branch 35, and would in large measure, if not entirely, depend upon the angularity of the substantially straight part of the bent portion of the branch 35 with the face of the lug of the 40 box. If this straight portion were inclined as shown in Fig. 10 then the angularity would be represented by the angle α formed by the lines *b* and *c*.

Therefore when the bent portion 36 of the 45 branch 35 is employed, it is immaterial whether the vertex of the angular portion 39 of the member 23 is sharp or rounded, for in either case the parts will function to produce the same results.

The spring means can appropriately be considered as two springs acting similarly and united to act conjointly upon the cam faces. It is of the foldable, hair-pin like type or somewhat V-shaped when viewed from the side. This type of spring designed as shown, with its branches 32 55 and 35 of substantially the same length, has little or no power to press at its coil portions upon the cover, and it is not relied upon in the present instance to exert any pressure at the coil portions upon the cover. 60

There is a decided point of difference between the instant spring means and that of the Mohun patent, namely in the instant case the spring means engages the cover considerably above the horizontal center line of the box opening which 65 enables the lower active edge of the member 23 to be correspondingly raised, thereby applying the cover closing force nearer the top margin of the box opening, which is a more advantageous point of application of the closing force, for it 70 has been found in practice that the upper portion of the cover is more apt to loosely seat than is the lower portion.

There is also a further and marked difference between the present construction and that of 75

the Mohun patent. In the instant case the lines *b* and *c* forming the angle *x* diverge upwardly, and the points of contact on the member *23* and cam face *4* against which the branches *35* and *32* are respectively held in spring-pressed engagement, react on the energized spring means tending to force it upwardly, that is to say there is a tendency of the upper portions of the spring means branches to move into the wider spaces above. Such movement is checked by the securing means *30* holding the spring means to the cover, a result being that the spring means exerts an upward pull on the cover, forcing the bottoms of the eyes *16* of the cover against the lower face of the pintle. This is highly desirable not only because it relieves the pintle from the weight of the cover and attached spring means, but also relieves the flange connection between the eyes and the cover from this weight and accordingly minimizes the danger of rupture at this locality due largely to this weight under the harsh service conditions that journal box covers are subjected to. Another result is that the branches *35* effect a turning action of the member *23* about the axis of the pintle in a downward direction toward and against the cover, thereby more firmly holding the member *23* closed and the cover closed upon the box.

To enable the securing means *30* to better withstand the upward pull of the spring means and the force of the weight of the cover downwardly, the securing means is provided, at each of its lateral free end portions, with a curved projection or lug *46* that extends for a substantial distance around the lower portion of the inner periphery of the adjacent spring coil which serves as an abutment against which the upward pull of the spring means and the downward pull of the cover acts.

In addition to the features already described which have an additive result in holding the member in closed position and the cover spring-pressed upon the box, another feature is present which further adds to the force exerted to hold the member closed upon the cover and the cover upon the box. This feature resembles somewhat the lever action made use of in the beforementioned Mohun construction and is dependent upon the relative locations of the axis of the pintle, the point of contact between the member *23* and the branches *35* (more accurately the line of contact), and the point *d*, the point of engagement (more accurately the line of engagement) of the member or hood with the cover. This lever action in the present instance is illustrated in Fig. 10 and will be understood by considering the line *e* which is drawn through the point *d* parallel to the line *c* (the cam face *4* of the lug) as the lever, and the point *f*, where the line *g*, drawn through the point *y* of the axis of the pintle perpendicular to the lines *c* and *e*, crosses the line *e* as the fulcrum of the lever. The longer arm of the lever is the portion of the line *e* between the points *f* and *d*, and the shorter arm is the portion between the point *f* and the point *h*, which is the point where the line *j*, drawn through the point of contact between the member *23* and branch *35* (in the present instance the point *a*) perpendicular to the lines *c* and *e*, crosses the line *e*. By so locating the various points, a lever is provided with the shorter arm above the fulcrum (above the axis of the pintle), and the spring means (branches *35*), in view thereof, produces a turning force upon the member *23*, tending to swing it about the fulcrum (axis of

the pintle) in a closing direction against the cover adding to the forces holding the member in spring-pressed closed position upon the cover and the cover spring-pressed upon the box previously described.

The position of the point *d* relative to that of the point *y* (the axis of the pintle) remaining fixed, this lever action will vary as the location of the point of contact (the point *a*) is varied, the force being decreased as the shorter arm is decreased and being a negative quantity when the point *a* crosses the line *g*. However as the final effect of the spring means upon the member *23* and cover *12* is due to the additive result of the lever feature and other features already described, and as the location of the various points mentioned in connection with the lever feature is also an important factor as regards the other features, it has been found in practice that the best results are obtained by locating the point *a* approximately as shown in the drawings.

It has been found in practice that in some instances there is a tendency for the free end of the branch *35* to follow a path directed toward its adjacent branch *32* when the member *23* is being swung toward the cover and to eventually override the branch *32*, or to come in contact with the roller *34* which causes a jamming of the parts and prevents the member *23* from being closed. To prevent this and to insure the branch *35* following its proper path, that is to say to insure its maintaining engagement with the sides of the angular portion *38*, the member *23* is formed with a depression *47* at its central portion between the angular portions *39* to provide a guide *48* for each of the branches *35* disposed at the inner side thereof and directed in a slanting direction at the lower portion thereof upwardly toward its respective branch, thereby, if occasion requires, guiding the free end of the branch *35* to insure its intended engagement with the sides of its respective angular portion *38*.

While, to facilitate an understanding of the basic principles of the invention and the functioning of the various parts, the presumed theory thereof has been described in conjunction with the showing made in Fig. 10, it is to be understood that this may not be entirely correct in all particulars and that it is not intended to limit the invention thereby or to the exact locations of the various parts as shown and described. The important novelty, however, as at present understood, resides in the combination of the various features which are united in so simple a construction to produce the spring action attained, the construction comprising merely four structural parts, namely a cover, spring means, spring means securing means, and a spring means energizing and retaining member in combination with a box which may be, as shown, of a standard type. Furthermore it will be understood that while in the preferred embodiment of the invention the several features described are all present to produce a resultant spring effect upon the cover, nevertheless it is within the purview of the invention to employ only that novel feature aforescribed relating to the construction of the member *23* and the spring means and their association whereby a final position of engagement between the member *23* and branches *35* is attained only after the spring means has been overenergized and then deenergized to its final position.

The invention claimed and desired to be secured by Letters Patent is:

1. A journal box lid comprising a cover for the

- journal box; a member; spring means disposed between said cover and said member for holding said cover upon said box in spring-pressed engagement therewith, said spring means having a portion comprising two coils having a connection with said cover, and a second portion comprising two branches extending upwardly, one from each of said coils, adapted, at a part thereof remote from said connection, for engagement with said box, said member having an articulation with said cover for swinging movement toward said cover from outward to inward position for energizing said spring means, said spring means comprising two other branches extending upwardly, one from each of said coils, each having the capacity, for swinging movement about said connection toward said part adjacent thereto from outward spring means deenergized position to inward spring means energized position, and each of said last mentioned two branches having a free end engaging said member, during said swinging movement of said member and said respective free ended branch, initially at said outward position and finally at said inward position of said member and said respective free ended branch; and a slanting guide for each of said free ended branches, carried by said member and disposed between the respective free ended branch and the box-engageable branch adjacent thereto, adapted to insure a free path for the free end of said respective free ended branch during said movement to inward position of said member and its said respective free ended branch.
2. In a journal box construction, a journal box having an opening; a lug having a cam face above said opening; a cover, spring-pressed upon said box over said opening and having pivotal connection with said lug; a hood having pivotal connection with said lug, a lower end spring-pressed upon said cover, and a spring-engaging inner face above the axis of said hood pivotal connection and spaced outwardly therefrom; and a U-shaped spring having a loop portion secured to said cover, an inner branch in spring-pressed engagement with said cam face, and an outer branch having an outer face in spring-pressed engagement with said hood inner face, whereby said hood and cover are yieldingly held in their closed positions, said hood and spring engaging faces being directed upwardly and outwardly to provide an upwardly diverging angle with said lug cam face, the pressure of said hood end upon said cover is increased on movement of said hood end away from said cover, and the resistance to separation of said hood end from said cover is increased due to the necessity of simultaneously further tensioning said spring.
3. In a journal box construction, a journal box having an opening; a lug having a cam face above said opening; a cover, spring-pressed upon said box over said opening and having pivotal connection with said lug; a hood having pivotal connection with said lug, a lower end spring-pressed upon said cover, and a spring-engaging inner face above the axis of said hood pivotal connection and spaced outwardly therefrom; and a U-shaped spring having a loop portion secured to said cover, an inner branch in spring-pressed engagement with said cam face, and an outer branch having an outer face in spring-pressed engagement with said hood inner face, whereby said hood and cover are yieldingly held in their closed positions, said hood and spring engaging faces being directed upwardly and outwardly to provide an upwardly diverging angle with said lug cam face, the respective inner and outer faces of said hood and spring adjacent the ends of said engaging faces diverging from said ends, whereby the pressure of said hood end upon said cover is increased on movement of said hood end away from said cover, and the resistance to separation of said hood end from said cover is increased due to the necessity of simultaneously further tensioning said spring.
